GIFT STOCKING

Ann E. Mohr, New York, N. Y.

Application March 15, 1951, Serial No. 14,507

Term of patent 3½ years

(Cl. D47—7)

To all whom it may concern:

Be it known that I, Ann E. Mohr, a citizen of the United States, residing at New York, in the county of New York and State of New York, have invented a new, original, and ornamental Design for Gift Stocking, of which the following is a specification, reference being had to accompanying drawing, forming a part thereof, wherein

Fig. 1 is a front view of a gift stocking, showing my new design;

Fig. 2 is a rear view thereof, and

Fig. 3 is an edge view thereof.

My design is characterized by the specific felt appliques arranged on one face of the gift stocking as shown, the Christmas tree representation being further decorated with sequins.

I claim:

The ornamental design for a gift stocking, as shown and described.

ANN E. MOHR.
